DESIGN FOR A PIN OR SIMILAR ARTICLE OF JEWELRY

Edmond Foret, New York, N. Y.

Application July 13, 1940, Serial No. 93,610

Term of patent 3½ years

To all whom it may concern:

Be it known that I, Edmond Foret, a citizen of France, residing at New York city, in the county and State of New York, have invented a new, original, and ornamental Design for a Pin or Similar Article of Jewelry, of which the following is a specification, reference being had to the accompanying drawing, forming part thereof.

Figure 1 is a face view of a pin or similar article of jewelry showing my new design; and Figure 2 is a side elevation of the same.

I claim:

The ornamental design for a pin or similar article of jewelry, as shown.

EDMOND FORET.
